MICROMETER GAUGE

Charles E. Linn and Paul H. Hummel, Lansing,
Mich., assignors to Automotive Service Tools,
Inc., Lansing, Mich., a corporation of Michigan

Application February 15, 1950, Serial No. 144,298

1 Claim. (Cl. 33—164)

1 This invention relates to micrometer gauges and particularly to special purpose gauges for measuring the clearance between the valve stem cap and the cap end of so called release type rotating poppet valves of internal combustion engines.

There is in general use a type of poppet valve called a release type rotating poppet valve. It is so named because when the valve is opened by the valve cam and tappet or valve cam, the pressure of the valve spring on the valve is released just prior to the opening of the valve, thereby relieving friction and permitting the valve to rotate slightly under any rotational force applied to it. Thus the valve is not apt to wear unevenly, thereby lengthening its life.

The present invention is a simple gauge for accurately measuring the clearance between the valve stem cap and cap end of such a valve so that adjustment may be made in the clearance between those two parts.

In the drawings accompanying this specification:

Figure 1 is a fragmentary cross-sectional view of an internal combustion engine having a poppet valve of the release type;

Figure 2 is a fragmentary cross-sectional view of a portion of the valve on an enlarged scale, showing the clearance between the valve cap and cap end of the valve;

Figure 3 is a similar cross-sectional view of the parts shown in Figure 2 with the clearance taken up; and

Figure 4 is a fragmentary cross-sectional view showing the present invention in use.

Figure 1 illustrates a portion of the engine block of an internal combustion engine 10. It is equipped with the usual cylinders and pistons 11, only one of which is shown. An exhaust valve of the release type rotating poppet 12 is mounted in a valve guide in the engine block. The stem of the valve is of uniform diameter for most of its length, but adjacent the stem end it is relieved at 13 to form a flat shoulder 14. See Figures 2 and 3. An annular valve spring retainer 15 surrounds the valve stem. It has a central opening somewhat larger than the greatest diameter of the stem. The spring retainer is provided with a central recess 16 around the opening which receives two semi-circular keys 17 which when placed together form a split ring 17. The opening through the keys when they are placed together is only slightly larger than the relieved portion 13 of the valve stem and smaller than the shoulder 14. The keys lock the

spring retainer on the valve and transmit the pressure of a valve spring 26 to the valve.

A hollow cap 18 fits loosely on the stem end of the valve. The depth of the interior of the cap 18 is slightly greater than the thickness of the shouldered end of the valve stem, thereby providing release clearance 19 between the cap 18 and the cap end of the valve stem. See Figure 2. This clearance should be between .002" and .006".

The valve is lifted by means of a cam shaft 20 through the medium of a push rod 21 and rocker arm 22 pivotally mounted on the engine block at 23. The push rod 21 is connected to the rocker arm by a short threaded stud 24 having adjusting nuts 25 thereon to permit the adjustment of tappet clearance between the rocker arm 22 and the cap 18. This clearance is the customary clearance to accommodate expansion of the valve and push rod and other parts as the engine becomes hot.

Due to the projection of the side walls of the cap 18 beyond the shoulder 14, when pressure is applied to the cap through the rocker arm 22 the cap 18 acts against the keys 17 and depresses the spring retainer 15 and spring 26 slightly before the cap 18 bottoms on the cap end of the stem of the valve 12. That takes up the clearance 19 and relieves the pressure of the spring against the shoulder 14 of the valve. See Figure 3. The only forces then preventing rotation of the valve are those due to friction between the valve guide and valve stem and between the cap 18 and the cap end of the valve stem. The valve may then slowly creep in a rotary motion due to the flow of exhaust gases around the valve head, as well as a slight rotating force imparted to the valve by the valve spring. This rotating motion tends to keep the valve head and valve seat clean and minimizes uneven burning from the flow of hot exhaust gases.

After the clearance 19 has been taken up, further movement of the rocker arm opens the valve in the usual manner.

In time the keys 17 will wear at their area of contact between them and the shoulder 14 of the valve stem. That wear may become so great that the clearance 19 may exceed the preferred maximum of ".006", causing greater movement between the valve cap and stem end of the valve when the valve is lifted.

It is desirable to check the clearance 19 periodically, and if it becomes excessive correct the same. That correction may be done in most instances by grinding off the edges of the side

wall of the cap 18 where they contact the keys 17. Of course, in correcting the clearance it is necessary to be sure that the walls of the cap 18 are not ground excessively so that the clearance becomes less than .002". The present invention is for the purpose of determining whether or not adjustment is necessary, as well as for determining when the proper adjustment has been made.

The present invention is a special micrometer gauge which consists of an inner sleeve 30, an outer sleeve 31, a central pin 32 and a set screw 33. The inner sleeve 30 has a cylindrical bore therethrough just large enough to be a loose sliding fit over the cap end of the valve 12. A portion of the exterior of the inner sleeve is threaded as at 34. An index mark 35 is scored on the outside of the sleeve. See Figure 4.

The set screw 33 is threaded through the wall of the inner sleeve 30. It is used for securing the inner sleeve to the pin 32, as will more fully appear presently.

The outer sleeve 31 is interiorly threaded intermediate its ends to cooperate with the threads 34. The interior of the outer end of the outer sleeve is provided with a bore of the same diameter as the bore within the inner sleeve 30. The end of the outer sleeve adjacent the valve stem is graduated as at 36 so that rotation of the outer sleeve relative to the inner sleeve will indicate contraction or elongation of the overall length of the two sleeves when rotated relative to the index mark 35. Preferably the graduations are such as to indicate relative axial movement of the two sleeves in thousandths of an inch.

The pin 32 is cylindrical and is a loose sliding fit within the bore in the sleeve 30 and the upper end of the sleeve 31. Preferably it is provided with an annular recess which receives a split ring 37 to prevent the pin from accidentally falling out of the two sleeves. The pin is accurately ground to a length equal to the overall length of the two sleeves when the index marks are set to indicate a zero reading.

To use the gauge the engine is dismantled sufficiently to gain access to the stem end of the valve 12. The cap 18 is removed from the valve stem and the inner sleeve slipped over the end of the valve stem and rested against the keys 17, as indicated in Figure 4. The set screw 33 is loosened to permit the pin 32 to engage the adjoining end of the valve stem. The set screw is then tightened to hold the pin firmly in place. As will be evident when that is done, the end of the pin opposite the valve stem projects out of the gauge. The cap 18 is then placed over the projecting end of the pin 32 and held against the adjoining end of the outer sleeve 31. The outer sleeve 31 is rotated sufficiently so that the cap will just contact the end of the pin. With the gauge contacting the keys 17, the pin 32 against the valve stem, the cap 18 against the other end of the pin, and the outer sleeve touch-

ing the cap 18, the gauge will indicate whether or not there is any clearance, and will register the amount of that clearance. If the clearance is less than .002" or more than .006" suitable adjustment should be made as previously described. The gauge can then be removed from the valve stem and the cap replaced thereon.

In the case of overhead valves such as shown, the present invention can be utilized in the determination and correction of the clearance between the cap 18 and valve stem without removing the valve. It can also be used in the determination of the clearance in the case of any other release type rotating poppet valve. In most of those cases, however, it is necessary to completely remove the valve from the engine in order to determine the clearance and correct the same if necessary.

From the foregoing it will be seen that the present invention provides an extremely simple and accurate gauge for determining the cap clearance between the cap and valve stem of valves of the release type. It is particularly useful in the case of overhead valves because it is unnecessary to remove the valve from the engine.

The scope of the invention is indicated in the appended claim.

We claim:

30 A micrometer gauge comprising inner and outer coaxial sleeves having portions thereof in overlapping relationship, one end of each sleeve projecting axially beyond the corresponding end of the other sleeve, said sleeves having cooperating 35 internal and external threads respectively on overlapping portions thereof and being open at both ends, cooperating indicia on external portions of said sleeves to indicate the overall expansion and contraction of the gauge, and a cylindrical pin received in said sleeves for axial movement, said pin being equal to the overall length of said sleeves when the latter are adjusted to predetermined relative setting, said pin normally projecting axially outwardly beyond the outer sleeve thereby providing a recess within the inner sleeve between the outer end of the latter and the corresponding end of the pin, and means for fixedly attaching said pin to one of said sleeves.
